UNITED STATES PATENT OFFICE

HAROLD BERNEY AND FRED BERNEY, OF MIAMI, FLORIDA

BOX FASTENER

Application filed August 5, 1929. Serial No. 383,503.

This invention relates to a fastener designed primarily for use with cardboard and like boxes for different purposes, one of the objects being to provide a novel form of fastening cord which, when assembled with a box and its cover, will serve to hold them against accidental separation and, at the same time, constitute a means whereby the box can be carried conveniently.

10 Another object is to provide a cord for the purposes mentioned which can also be used to hold the contents of the box under pressure and keep them from shifting and becoming mussed while the box is being carried.

15 With the foregoing and other objects in view which will appear as the description proceeds, the invention resides in the combination and arrangement of parts and in the details of construction hereinafter described and 20 claimed, it being understood that changes in the precise embodiment of the invention herein disclosed may be made within the scope of what is claimed without departing from the spirit of the invention.

25 In the accompanying drawings the preferred form of the invention has been shown.

In said drawings,

Figure 1 is a perspective view of a telescope box having its parts held assembled by the 30 fastening means constituting the present invention.

Figure 2 is a vertical longitudinal section.

Figure 3 is a section on line 3—3, Figure 2.

35 Figure 4 is a horizontal section through one end portion of the cover showing one of the cord-receiving slots.

One form of box with which the invention can be used has been illustrated in the drawing and is of the "telescope" type including a 40 body 1 and a cover 2 adapted to slip onto and around the body. The parts can be made of heavy cardboard, imitation leather or other material.

Formed in the sides of the body 1 are slots 45 3 each of which opens into a notch 4 at the free edge of said side and terminates, at its inner end, in an extension 5 disposed at right angles to the main portion of the slot and along the longitudinal center of the side of the body. This extension opens into an aper-

ture or eye 6. The two extensions 5 in each side are extended toward each other and the apertures or eyes 6 in each side are directly opposite the corresponding ones in the opposite side.

The sides of the cover 2 are also provided with slots 7 extending thereinto from the free edges thereof, there being notches 8 at the outer ends of the slots while the inner ends of the slots 7 open laterally into eyes or openings 9 intersecting the longitudinal centers of the sides. Slots 7 in each side of the cover 2 are closer together than are the slots 3 but the openings or eyes 9 are located where they will register with the openings 6 when cover 2 is properly positioned on the body of the box.

Notches 10 may be formed in the free edges of the sides of cover 2 between the notches 8 to receive fingers of the user when it is desired to slide the cover upwardly off of the body of the box.

A cord has been indicated at 11 and the ends thereof are fastened together in any suitable manner. This cord is so proportioned as to be capable of extending across the box from side to side thereof where the openings 6 and 9 are located and to provide a handle portion 12 along the outer side of the cover.

In practice the body portion 1 is packed with the garments or other fabrics to be carried after which the cord 11 is extended across the body and inserted into the notches 4 which, in turn, guide the cord into the slots 3, their extensions 5 and the openings or eyes 6. The cover 2 is then pressed downwardly around the body 1, notches 8 receiving the cord and guiding it into slots 7 and thence to openings 9. The openings 6 and 9 will register and by lifting the closed box by means of the handle portion 12 the cord will be drawn taut, fasten the cover to the body, and press the contents firmly against the bottom of the body.

What is claimed is:

1. The combination with a box including a body and a cover adapted to telescope, there being registering openings in the opposed sides of the body and cover, each opening

having a slot extending therefrom to the free edge of the part in which the opening is formed, of an endless loop insertable through the slots into the respective openings and 5 providing portions extending transversely within the box and a handle outside of the box.

2. The combination with a box including a body, a cover adapted to telescope therein, there being spaced apertures in opposed sides of the body and cover, the corresponding apertures in the body and cover being adapted to register when the box is fully closed, of endless loop shiftable into the sides 10 of the body and cover from the free edges thereof and adapted to be seated in the apertures to fasten the cover to the body.

3. The combination with a box including a body and cover adapted to telescope, there 15 being spaced apertures in opposed sides of the cover and body, all of the corresponding apertures being adapted to register when the box is fully closed, there being a slot extending from each aperture to the free 20 edge of that side of the body or cover in which it is located, of an endless flexible loop insertable laterally into the slots and the alining apertures, said loop having a portion outside of the box constituting a handle, said loop being provided with spaced portions extending across the interior of the box to bind the contents of the box against the body 25 when the loop is taut.

4. A box including a body and a cover 30 adapted to telescope, there being spaced apertures in each of two opposed sides of the body and cover, and slots extending from the free edges of said sides to the respective apertures, the corresponding apertures in the 35 body and cover being adapted to register for the reception of a fastening element insertable longitudinally of the slots into the apertures to hold the cover to the body, to engage the contents of the box, and to provide 40 a handle.

In testimony that we claim the foregoing as our own, we have hereto affixed our signatures.

HAROLD BERNEY.
FRED BERNEY.
